UNITED STATES PATENT OFFICE.

HARRY SIEGEL, OF NEW YORK, N. Y.

DESIGN FOR A BLANKET FASTENER.

Application filed July 6, 1927. Serial No. 22,672. Term of patent 14 years.

To all whom it may concern:

Be it known that I, HARRY SIEGEL, a citizen of the United States, residing at New York, in the county and State of New York, have invented a new, original, and ornamental Design for a Blanket Fastener, of which the following is a specification, reference being had to the accompanying drawing, forming a part thereof.

I claim:

The ornamental design for a blanket fastener, as shown.

HARRY SIEGEL.
